(Cl. 12—14)

This invention relates to a stretching and toe lasting machine for boots and shoes whereof the lip of the uppers is pulled or folded towards the inside, comprising co-operating pincers and wipers for cement-lasting, similar as for the heel-lasting. In the hitherto known lasting machines of this kind the pincers are mechanically combined with the wipers in such a way that their movements relate to each-other whereby the pincers are guided by vertical or oblique guide bars which, however, interfere with the control means to be arranged and with the required supports for the shoe last. In the case of such machines a cementing material is used wherewith the uppers to be stretched or pulled are coated prior to or during the lasting work. The machines in question have many defects, particularly that the main movements of the machine are mechanically so effected that an interruption of the motion is no more possible after the start of the working operation; the folds formed are of irregular shape and therefore undesired; besides, the uppers are not well stretched.

The new machine according to this invention which eliminates the above mentioned defects adds substantial and new features to the toe lasting which make it possible to simultaneously combine the stretching of the uppers with the folding and lasting respectively. The wipers and pincers are of similar shape so that sufficient space remains underneath the pincers for the installation of the necessary control gears and supports. The forming pincers for pulling the uppers over the last are flat horse-shoe shaped parts similar to shears and are located, nearly parallel, directly underneath the well-known also horse-shoe shaped wipers; they are actuated in couple-connection by the movements of the wipers. The pairs of forming pincers grip the uppers of the shoe-toe by their whole horse-shoe shaped surface and not only by points. During this operation, the wipers are connected to a controlled wiper slide, and separate from it are the pincer-pairs connected to another also controlled pincer-slide so that both wipers and pincers, though they are independent in mechanical respect are correspondingly moved. The wiper-slide is guided on a main slide actuating the control-gears of the individual parts by its movements. Thus, the machine consists of four main parts, namely the machine housing, the main slide guided on the main housing, the wiper slide guided on the main slide, and the pincers-slide guided on the machine housing. The machine is driven by compressed air or hydraulically whereby it has been

made possible to stop the machine at any position or to reverse its motion. It has been achieved by the suitable construction of the forming pincers that the uppers are gripped by the pincers so long until they have been gripped by the wipers. To ensure a safe support, last-feelers, sole- and ball-pressers and heel holders are arranged which are controlled by compressed air or mechanically, whereby double-sole-pressers (pressure feet) prevent any undesired displacement or shifting of the insole. The forming pincers and sole-pressers are so controlled that the shoe-last from the tip on is only gradually released in order to let the wipers turn it. All important parts are locked and so arranged that even the slightest return movement into the starting position is prevented. The wipers are heated in the well-known manner.

The drive for the individual stages of operation 20 is effected through a new control valve which follows the control steps of a pedal.

An example of the structure of the new machine may be as follows, as illustrated in the attached drawings:

25 Fig. 1 is a side view of the whole of the machine, partly with sections of individual parts.

Fig. 1a shows the gearing of a cam-control.

Fig. 1b shows a control yoke seen in the direction of arrow c of Fig. 1.

30 Fig. 2 is a section on line I—I of Fig. 1.

Fig. 3 shows the machine part according to Fig. 2, seen from above.

Fig. 4a, b, c show the various positions of the wipers and forming pincers during the lasting 35 operation.

Figs. 5 and 6 illustrate the control valve for the compressed-air control, seen from two sides, partly in section.

Fig. 7 shows the positions of the valve stems 40 and cams at the three steps I, II, III.

Fig. 8 is a view from above of the wiper slide with the forming pincers, wipers, feelers, and drive for the pincers.

Fig. 9 shows the wipers with a heating arrangement.

Fig. 10 shows the cam path according to Fig. 1a in section on line III—III of Fig. 11.

Fig. 11 shows the four main parts of the machine according to Fig. 1 with the main drive.

50 Fig. 12 shows a part of the machine in the side view, partly in section.

The new stretching and toe lasting machine consists of four main parts, namely the machine housing A, the main slide B, the wiper slide C, and the pincers-slide E (Fig. 11). The main slide

B slides on the slide-ways 6, Figs. 1 and 11 of the housing A, whereas the wiper slide C with the guide 39 slides on the main slide B. On the housing A, an overhang and sliding machine-body D is mounted which carries the supporting devices for the shoe-last. The pincers-slide E slides on the housing A.

The main movements of the above parts are as follows:

The main-slide B with the wiper slide C slides on housing A. The wiper slide C slides in relation to the main slide B, and the driving gears of the supporting body D depend on the relative movements between main slide B and housing A and between main slide B and wiper slide C, Figs. 1 and 11.

On housing A a pressure cylinder 2 is fixed whose piston 2a is connected by its piston rod 4 with a butt strap 3 at joint 3a. At the other end of butt strap 3, i. e. at joints 3b a swing-lever 5 is turnable about the axis 5a. This lever bears a toothed arc 67 at its other end (Fig. 11). Furthermore, this lever 5 bears also a roller 7 which rests on cam 8. This cam has double curves 8 and 8a (Figs. 1a and 10), and swivels round the pin 68 in the main slide B. The toothed arc 67 meshes with rack 69 on wiper slide C.

On wiper slide C another pressure cylinder 24 is arranged whose piston is connected with yoke 25, Figs. 1 and 1b, swivelling at pivot 26. On top of yoke 25 a swing-arm 27 is pivoted carrying the ball-presser 28. On the side of yoke 25 a control device with the rods 37, 38 is mounted which are connected with the curves 8 and 8a at joint 64. The lower joint 26 is coupled with butt strap 62 which is connected through a hinged joint strap 29 with the pivoted stop pin 30. This stop pin 30 is situated on a locking rock 31 (fluted) which is connected to the feelers 32 with springs 33. Joint strap 29 is also connected with the bell crank 35 which is provided with a cam 35a for pressing the locking pin 36 against rock 31.

On the shaft 5a a bevel gear system 42 with pinion 43 is mounted. This pinion 43 and also the pinion 44 on axle 45 mesh with a displaceable toothed rack 63. Pinion 43 is supported in the main slide and pinion 44 in the housing A. On the axle 45 cams 46, 47 and the worm gear 52 are fitted. Cam 46 actuates through roller 48 the front sole-presser 49, and cam 47 through roller 51 the rear sole-presser 50.

On the axle 68 of the cams 8 a toothed wheel 13 is fitted which meshes with rack 12 on the pressure cylinder 2 and with a pinion 14 on lever 64. This lever 64 actuates through a connecting rod 15 the lever 65 which is supported at 20 and provided with a friction clutch. Lever 65 is connected with the heel-holder 16. For locking purposes, a locking pin 17 and a fluted locking cleat 18 are provided.

The worm gear on axle 45 actuates the cams 53 upon which the rollers 54 of the pincers-slides E, 55 are running, Figs. 1 and 2, sliding on the slide-guides 66 of housing A. On the slides 55 the forming pincers 9 and 10 are pivoted at 70 above which the wipers are abutting, nearly in parallel. The top pincers 9 can be deflected against the bottom pincers 10, due to their spring action. These pincers have nearly the shape of a horse-shoe and consist of members moving towards each other, in order to be adapted to the shape of the respective last. The wipers 40 have the similar usual shape, but are connected with the slide-guide 39 on the upper or wiper slide C,

Figs. 1 and 8. As Fig. 8 shows, on slide 39 an arrangement of separately operating feelers and wipers is provided. The feelers 32 with the feeler-holders 73 are subjected to the pressure from spring 33. Three feelers 32 are arranged, namely two on the sides and one at the tip. The adjustment of the plates 72 of the wipers is effected by means of a hand-wheel 74, Fig. 1, through a spindle 75, Fig. 8 connected with the block 76 upon which toothed bars are mounted. The latter bars mesh with pinion 58 the axle of which bears another pinion 59 gearing with the toothed arc of the plates 72 and adjusting these plates.

Figs. 4a, 4b, 4c illustrate the operation method of the wipers and forming-pincers. Above the wipers 40 the feelers or fingers 32 are arranged. Below the wipers the two forming pincers 9, 10 are arranged of which each differs from the other. The top pincers 9 are provided with a row of holes 56a, Fig. 3, which are faced by the bolt heads 56 of the bottom pincers 10. The bolt heads enter into the holes 56a when the pincer-pairs are closed, Fig. 4b: in this case it must be noticed that the wipers 40 are supported on the wiper slide, and the pincers 9, 10 in the slides 55 on the housing 1. The wipers are electrically heated, Fig. 9. The machine is driven in a new manner by means of compressed air through a treadle control F, Fig. 1, where the control steps or notches 1 and 22 are provided. This control leads to a new valve controlling device 23, Figs. 1, 5 and 6, the control steps of which are shown in Fig. 7. The valve gear 23 controls the admission of compressed air through the pipe lines 77 into cylinder 2 and through line 78 into cylinder 24 on the wiper slide. The valve gear comprises a valve body 23, Figs. 5 and 6, in which a cam shaft 79 with three cams 60 is journalled. The cam shaft is turned by the crank 80 of the treadle control. The cams 60 actuate the valve stems 61 and are interlocked so that according to the position of the control notches 0, 1, 22 the three stems are kept each in a different position. When changing from the first notch 0, i. e. the neutral position, into the second notch 1 the position II results of Fig. 7, that means, the stem 61 of the first cam 60 is pushed in (IIa) and the compressed air is admitted to the top of cylinder 2 whereas the other stems (IIb, IIc) are at rest. When changing is continued into the third notch 22, position III results as per Fig. 7. In this case the stems IIIa as well as IIIc have been pushed down, so that compressed air flows through line 78 also to the wiper slide cylinder 24; reversing back into the 0-notch then position I results where only the second stem 1b is pushed down for the admission of compressed air under the piston 2a. Fig. 7 illustrates also the position of the crank 80 at every position of the reversing lever.

The machine works as follows:

By displacing the pedal F, Fig. 1, into the second notch 1, the position of the valve 23 is changed into position IIb, Fig. 7. This causes compressed air to flow through line 77 into cylinder 2 above the piston 2a. Piston 2a is moved in the direction of arrow b and drives the connecting rod 3 by means of piston rod 4 at its end 3a. On the housing A, two cylinders 2 of this kind with the moving rods are fixed by bolts. When piston 2a with its connecting rod 3 moves, the main slide B together with the wiper slide C and with the parts belonging to it is moved down in the direction of arrow b. This has been made possible, because the cam 8 locks roller 7 and

therefore, the roller arm 5 cannot swivel about its axis of rotation 5a, Figs. 1 and 11. The middle portion of the main slide B is hollow Fig. 10, and separate moving means 3, 5, 7 are provided on each side of the slide, in fact, all outer parts are provided in double (one on each side).

The down movement of the main slide B causes other special movements. The rack 12 rigidly fixed on cylinder 2 turns the pinion 13 being lowered in the direction of arrow b. Pinion 13 actuates pinion 14 with its splined axle, thus causing a swing movement of the butt strap 64. This movement is transmitted through the rods 15, 20, 65, 19, whereby the heel holder 16 is pressed against the shoe-last. This heel holder is provided with an air cushion or the like on its inner surface, in order to save the fine quality uppers and to ensure a close abutting. As soon as the heel holder is resisted by the shoe-last it is locked along with the fluted bolt 17 in the fluted rack 18 which is connected with the lever 65. The friction clutch 20 serves for balancing small differences in size of the shoe-last and, besides this, the size of the respective last is met with by an adjustment of the bolt 11a in the notched rack 18. The heel height of the last is adjusted by another adjusting arrangement 81.

When the main slide B is lowered, also the wiper slide C with the wipers 40 is lowered. Thereby, the wiper-parts 40 exert pressure upon the forming pincers 9, Figs. 2 and 4a—c and deflect them against the clamping springs 82, until they rest upon the bottom pincers 10. As the shoe uppers have been already inserted before between the top and bottom pincers 9 and 10, the leather is now gripped by both pincer pairs. To ensure a safe gripping, during this movement the bolt heads 56 enter into the holes 56a of the top pincers 9 and clamp the uppers there fast, Fig. 4b. The bolts are of a longer size at the side of the bottom pincers 10, in order to keep the uppers there somewhat longer for the following lasting operation. Thereby it has been achieved that the folds formed at the shoe tip are kept small and of regular shape so that the hitherto irregularly placed, thick, and undesired wrinkled folds are eliminated. The uppers gripped by the pincer pairs, 9, 10 are stretched down so far as per Fig. 4b until the pincers are underneath the edge of the insole. This movement is effected by the cams 53 on the rollers 54 with the slides 55, Fig. 2.

The cams 53 are actuated through a shaft 45 and a worm gear 52 by a pinion 44 which meshes with the rack 63. This rack is lowered down together with the main slide B and actuates by means of pinion 44 the shaft 45, the cams 46 and 47 for the sole-pressers 49, 50, and the worm 52, so that the position of Fig. 4b is reached. Herewith, the first working operation is finished. Now, an operator may conveniently grasp the two levers 21 (Figs. 2 and 3) and manipulate them to additionally actuate the forming pincers, whereby the uppers on the top of the shoe last may be adjusted, if necessary.

For the second operation, the treadle control F is displaced into the second notch 22, and the valve gear position III, Fig. 7, is engaged at cam 23 so that compressed air flows also into the top cylinder 24 on the wiper slide. The main cylinder 2 remains under the hitherto existing pressure whereby the movement of the piston remains stopped by the stop dog 11. The piston 11 of cylinder 24 is now moved in the direction of arrow a and turns the yoke 24 about its ful-

crum 26. At the same time, the ball presser 27 is moved forward and brought at rest on the shoe-last. The applied surface of the ball presser is designed as an air cushion 28 or the like which suits well any shape of the last, makes a close fit, and saves the fine uppers. By the movement of yoke 25 the butt strap 26 rigidly connected with it is caused to swing out; this movement is transmitted through the butt strap 29 on the one hand up to the finger lever 30 and through the butt strap 34 to the cam lever 35 with cam 35a on the other hand. The finger lever 30 is supported in the wiper slide. When the finger lever has swung off the locking rack 31 in consequence of the movement of butt strap 29, then, the thereby released feeler holders 73 are shifted by their springs 33 towards the shoe-last and adjoin against same. Three feelers 32 are arranged, Fig. 8, of which the one is directly applied to the tip and the two others to the sides, whereas the three respective feeler holders 73 may be shifted horizontally side by side in the wiper slide. After the feelers 32 have been pressed against the shoe-last they must be locked. This is effected by means of the cam lever 35, namely, this lever is swung by butt strap 34, so that its cam 35a is pressed against the fluted locking pin 36 which in turn presses the locking rack 31 against the feeler holders 73, thereby locking the feeler holders (Fig. 12).

The control gearing 37, 38, 8 is also mounted on yoke 25 and joins in the movements of the yoke whereby the curves 8, 8a supported by axle 68 are swivelled. At the same time, roller 7 on the lever 5 is thereby released so that it can be swivelled about its fulcrum 5a by means of the connecting rod 3 (which is still being moved downwards under the piston pressure). Thereby, roller 7 moves along curve 41.

The toothed arc 67 gearing with rack 69 is also swivelled together with lever 5 and shifts the rack together with the wiper slide 39. Together with the slide 39, the wipers 40 (Figs. 1 and 8) are also displaced folding the uppers L which have been stretched before by the forming pincers 9, 10, over the edge of the last and then pressing onto the insole. During this, the wipers are also turned about their hinge point 84 by means of the arrangement provided according to Fig. 8.

As lever 5 swings about 5a, the bevel gear 42 is also driven and turns through the second bevel gear, the pinion 43 transmitting the movement onto the rack 63 which slides in the main slide B. When rack 63 is moved, the pinion 44 is turned and also the shaft 45. This is the second movement of shaft 45 (the first is effected when the main slide B is lowered) which causes the action of the sole-pressers or press-feet 49, 50, in the right moment. In order to ensure that the wipers can sufficiently swivel-in, it is necessary to lift off or deflect the front sole-presser 49. This is done by the special curve 46 and roller 48, the rear sole-presser 50 giving still sufficient support in this case. As during the lasting-operation the rear sole-presser 50 is at a higher level than the wipers, it must, all lasting-operations being finished, be also swivelled downwards that is effected by means of cam 47 and roller 51. Now, the wipers bring the uppers L to a perfectly close fit on the insole 85, Fig. 4c. In order to have the heel of the last also joined in this movement, it is arranged displaceable so that it is also somewhat lowered together with the rear-press-foot 50.

When the machine is brought back into the

starting position by the third command, i. e. notch 0, position I of the valve gear, Fig. 7, appears, that means, line 78 is disconnected from cylinder 24 at the position Ic of the valve gear, also line 11 from the top inlet of cylinder 2 at the position Ia of the valve gear, whereas line 11 opens into the bottom inlet of cylinder 2 at the position Ib. The piston 2a and together with it the connecting rod 3 and the main slide B with the wiper slide C are pressed upwards again, and all before described movements are made in the reverse sense so that the machine is again in its starting position.

Fig. 9 shows the heating arrangement for the wipers comprising an electrical heating element 86 placed in the wipers.

What I claim is:

1. A shoe shaping and toe lasting machine performing cementation, stretching and simultaneously toe lasting of uppers of shoes or boots, comprising movable wipers, means connected with

said wipers for adjusting the same, divided pincers of similar shape as the wipers, said wipers being disposed over the pincers and adapted to close the pincers for gripping the lip of the uppers stretched on the last, a slide carrying said wipers, another separate slide carrying said pincers, and means actuating said slides.

2. A toe lasting machine having cooperating wipers and pincers, the pincers comprising two horse-shoe shaped pairs arranged one above the other, the upper pair of pincers being resilient, said wipers being adapted to engage the upper pair of pincers and swing them against the lower pair of pincers, means rigidly supporting the lower pair of pincers, a separate slide carrying said wipers, and means for actuating said slide.

3. A toe lasting machine having cooperating wipers and pincers, the pincers comprising two horse-shoe shaped pairs, arranged one above the other, the upper pair of pincers being resilient, said wipers being adapted to engage the upper pair of pincers and swing them against the lower pair of pincers, the upper pair being provided with a row of holes formed at its inner rim, both carried by the lower pair and entering in the holes of the upper pair when the upper pair is swung against the lower pair, a slide carrying said wipers, and means for actuating said slide.

4. A toe lasting machine having cooperating wipers and pincers, the pincers comprising two horse-shoe shaped pairs arranged one above the other, the upper pair of pincers being resilient, said wipers being adapted to engage the upper pair of pincers and swing them against the lower pair of pincers, the upper pair being provided with a row of holes formed at its inner rim and both heads carried by the lower pair and adapted to enter into the holes of the upper pair, the bolt heads being longer at the sides of the pincers than at the lip whereby the uppers are maintained longer there for the following lasting operation.

5. A toe lasting machine having pincers and wipers of similar shape, the pincers comprising two horse-shoe shaped pairs for gripping a last, one of said pairs being situated above the other, the upper pair being resilient and adapted to be actuated by said wipers to swing against and onto the lower rigidly supported pair, said wipers comprising a pair of wiper-members also of horse-shoe shape, and means for moving said wipers in the same direction as the pincers.

6. A toe lasting machine having pincers and wipers of similar shape, the pincers and wipers

comprising horse-shoe shaped pairs for gripping a last, each pair operating like shear blades, a movable slide for guiding the wipers, another separate slide moving in a perpendicular direction to the first mentioned slide and carrying said pincers.

7. A toe lasting machine having pincers and wipers of similar shape, a pincer slide carrying said pincers, a wiper slide carrying said wipers, the two slides moving in a perpendicular direction one to the other, a main slide, a frame having a guideway for the pincer slide and another parallel guideway for the main slide, whereby the main slide is moved parallel to the pincer slide, said main slide having a guide for supporting the wiper slide and moving it in a direction perpendicular to the movement of the main slide, this main slide having means to control the movements of the two other slides, namely, the pincer slide and the wiper-slide.

8. A toe lasting machine having pincers and wipers, a pincer-slide carrying said pincers, a wiper slide carrying said wipers and a main-slide, the main-slide controlling the movements of the pincer-slide and wiper-slide by means of a piston-cylinder device comprising two cylinders, pistons within said cylinders, a pedal-actuated valve gear, controlling said pistons, a main frame, one of said cylinders being fixed on the main-frame, means connected with the piston in said one cylinder for actuating the main-slide, the other cylinder being fixed on the wiper-slide, and means connected with the piston in said other cylinder for actuating the wipers arranged on the wiper-slide.

9. A toe lasting machine having pincers and wipers, a pincer-slide carrying said pincers, a wiper slide carrying said wipers, and a main-slide, the main-slide controlling the movements of the pincer-slide and wiper-slide by means of a piston-cylinder device comprising two cylinders, pistons within said cylinders, a pedal-actuated valve gear, controlling said pistons, a main frame, one of said cylinders being fixed on the main-frame, means connected with the piston in said one cylinder for actuating the main-slide, the other cylinder being fixed on the wiper-slide, means connected with the piston in said other cylinder for actuating the wipers arranged on the wiper-slide, and releasable locking means controlled by the wiper-slide and pivotally connecting the piston in said one cylinder to the main slide.

10. A toe lasting machine having pincers and wipers, a main-slide, a wiper-slide carrying said wipers and a pincer-slide carrying said pincers, piston-cylinder devices effecting the movement of the main slide and wiper-slide and causing the main-slide to control the movements of the pincer slide and wiper slide, means pivotally connecting the main slide with the piston of the cylinder actuating the main slide, a driving device transmitting the piston movement to the wiper-slide, and means temporarily locking said driving device.

11. A toe lasting machine having pincers and wipers, a main-slide, a wiper-slide carrying said wipers and a pincer-slide carrying said pincers, piston-cylinder devices effecting the movement of the main slide and wiper-slide and causing the main-slide to control the movements of the pincer slide and wiper slide, means pivotally connecting the main slide with cylinder actuating the main slide, a driving device transmitting the

piston movement to the wiper-slide, this driving device comprising a rocking lever connected with the piston and having a toothed segment, a rack connected with the wiper slide and meshing with said segment, and a gear system actuated by said lever, and a control device for the pincers and sole-pressers, said control device being actuated by said gear system.

12. A toe lasting machine having pincers and wipers, a main-slide, a wiper-slide carrying said wipers and a pincer-slide carrying said pincers, piston-cylinder devices effecting the movement of the main slide and wiper-slide and causing the main-slide to control the movements of the pincer slide and wiper slide, means pivotally connecting the main slide with the piston of the cylinder actuating the main slide, and a control device regulating a heel-holder and connected to said cylinder.

13. A toe lasting machine having pincers and wipers, a main slide, a wiper-slide carrying said wipers and a pincer-slide carrying said pincers, feelers and pressers, and piston-cylinder devices effecting the movement of the main slide and wiper-slide, the cylinder devices comprising a main-cylinder fixed on the machine-frame and a cylinder fixed on the wiper-slide, the latter containing a piston connected to a member actuating and controlling the feelers and the pressers.

14. A toe lasting machine having pincers and wipers, a main-slide, a wiper-slide and a pincer-slide, piston-cylinder devices effecting the movement of the main-slide and the wiper-slide and a valve control device comprising three valves adjustable for three combinations of different positions, the adjustment of the valves being effected by a pedal-drive.

15. A toe lasting machine having pincers and wipers, a main-slide, a wiper-slide and a pincer-slide, piston-cylinder devices effecting the movement of the main-slide and the wiper-slide and a valve control device comprising three valves adjustable for three combinations of different positions, the adjustment of the valves being effected by a pedal-drive, connected to a crank and its crank-cam-shaft, the cams of which engage the valve stems for one step of the movement of the working members of the machine.

16. A toe lasting machine having pincers and wipers, a main-slide, a wiper-slide and a pincer-slide, piston-cylinder devices effecting the movement of the main- and the wiper-slide, a valve-control device and a main-device connected to the main cylinder piston, the main-device comprising a lever pivoted on the main-slide, this lever being provided with a toothed segment, with a ratchet wheel and a bevel gear, the ratchet wheel resting on a releasable locking mechanism and the bevel gear being connected to the control device of the pincers.

17. A toe lasting machine having pincers and wipers, a main-slide, a wiper-slide and a pincer-slide, piston-cylinder devices effecting the movement of the main-slide and the wiper-slide and a valve control device comprising three valves adjustable for three combinations of different positions, the adjustment of the valves being effected by a pedal-drive, the movement of the main-slide being adjustable within certain limits.

HEINRICH WALther, Sr.
